UNITED STATES PATENT OFFICE

2,260,001

PISTON AND LINER

David Bushby, Regina, Saskatchewan, Canada,
assignor to The Vacuum Air Pressure Company
Limited, Regina, Saskatchewan, Canada

Application April 27, 1940, Serial No. 332,056

4 Claims. (Cl. 309—12)

My invention relates to improvements in pistons, the principal object of the invention being to provide a device of the character herewithin described consisting of the combination with a specially machined piston of a removable liner therefor, which when worn may be removed and a new liner substituted therefor.

A further object of my invention is to provide a device of the character herewithin described which embodies the combination with a specially machined piston of an adjustable split liner and shim-rings which may be transferred from a special ring groove at the upper end of the liner to a shim groove at the lower end of the liner as the liner itself becomes worn.

With the above more important objects in view and such other minor objects as may appear as the specification proceeds, my invention consists essentially in the arrangement and construction of parts all as hereinafter more particularly described, reference being had to the accompanying drawing, in which:

Figure 1 is a side elevation partly in section of my special piston and illustrating the replaceable liner therefor.

Figure 2 is a sectional elevation along the line 2—2 of Figure 1.

Figure 3 is a side elevation partly in section illustrating my piston and special adjustable split liner in the unworn position.

Figure 4 is a fragmentary sectional elevation illustrating the embodiment of Figure 3 in worn or adjusted position.

In the drawing like characters of reference indicate corresponding parts in the different figures.

The piston 1 of the embodiment of my invention illustrated in the accompanying Figures 1 and 2, is provided around the upper end of the wall 2 thereof with conventional annular ring grooves 3, for compression and oil rings collectively enumerated 4. The outer surface 5 of the piston wall is however tapered by machining around its circumference, inwardly toward the base from a plane medially of its length and transverse to the axis of the piston, this plane being preferably somewhat above the intermediate transverse plane of the piston.

Designed to engage with the tapered surface 5 of my piston is a removable and replaceable liner 6 having an outer cylindrical surface 7 and an inner surface 8 tapered complementarily to the surface 5 of the piston.

The liner 6 is retained in position upon the piston by means of the pins 9, which extend

through drillings adjacent the skirt or lower end 11 of the piston and project into aligned recesses 12 drilled partially through the thickness of the liner from the inner surface thereof, these pins being provided with pointed inner ends 13, which project upon the interior 14 of the piston wall and are capable of being engaged by complementarily shaped conical apertures in a split retaining ring 15.

From the foregoing it will clearly be perceived that I have provided simplified means by which my liner may be preserved very rigidly in place during its period of service.

Proceeding now to describe my piston and adjustable liner as illustrated in the accompanying Figures 3 and 4, it will be noted upon reference to these illustrations that my piston 16 bears a close resemblance to the piston 1 insofar as both are provided with conventional compression and oil rings positioned in annular ring grooves adjacent the upper ends thereof, the piston 16 being also tapered by machining uniformly around its circumference and inwardly towards the base as at 17.

In this embodiment of my piston, however, I provide annular grooves 18 and 19, the former of which is machined approximately at the transverse plane where the tapered surface 17 commences while the latter is machined around the skirt or adjacent the lower edge 20 of my piston.

The adjustable liner 21 employed with this embodiment of my invention is split diagonally as at 22, the split edges, however, being at right angles to the upper and lower circumferential edges 23 of the liner as at 24, although the particular form of division illustrated in the accompanying Figure 3 is not of course essential.

The inner surface of my liner 21 is set at the upper edge as at 25 to engage with the lower of a pair of retaining rings 26 positioned in the groove 18, a similar pair of rings 27 being positioned in the groove 19.

The lower edge 28 of my split adjustable liner bears against the uppermost of the rings 27 and between this pair of rings and the pair of rings 26, may be interposed shim rings 29, by means of which my adjustable liner 21 may be maintained at progressively advanced positions upon the piston according to the amount of wear upon the surface 21 thereof.

In Figure 3 I have shown my liner in the position it would occupy when new or unworn and in this illustration it will be seen that the shim rings 29 are interposed between the retaining rings 26.

When slightly worn, however, the liner may

be temporarily removed for the transfer of one of the shim rings to a position in the groove 19 and between the retaining rings 27 (after the liner has been replaced), while again, after still further wear has taken place another of the shim rings may be transferred from between the retaining rings 26 to a position between the retaining rings 27 as illustrated in the accompanying Figure 4.

Finally in connection with this description of the embodiment of my invention illustrated in the accompanying Figures 3 and 4, I would point out that the retaining rings 27 may themselves be maintained in place if desired, by means of the stepped lock ring 30 of the configuration clearly illustrated and which in its turn is maintained in position by cotter pins 31, which extend through apertures in the skirt of the piston or adjacent the lower edge 28 thereof.

It will be noted that in the several figures illustrating the two embodiments of my invention above described, I have shown a particular piston pin mounting arrangement collectively enumerated 32, via which the connecting rod 33 is secured. The same forms no part of the present specification, however, the same being more fully illustrated, described and defined in my patent application Serial Number 314,004.

What I claim as my invention is:

1. In combination a piston and removable liner therefor, annular ring grooves in said piston wall adjacent the upper end thereof, said piston being tapered inwardly towards the base from a plane medially of its length and transverse to its axis, said liner surrounding the tapered portion of said piston in the manner of a sleeve and being tapered complementarily upon the inner surface thereof, a plurality of apertures extending through said piston on a plane transverse to the axis thereof, adjacent the lower edge of said piston, and pins projecting through said apertures for retaining said liner upon said piston.

2. The device as defined in claim 1 in which said pins are designed to extend into recesses formed extending partially through the thickness of said liner from the inner surface thereof, said recesses being aligned with said apertures, and a split ring provided with a plurality of recesses therein extending around the inner surface of said piston, the projecting ends of said pins being receivable into said recesses.

3. A piston and an adjustable liner positioned thereon, said piston being circumferentially tapered inwardly towards the base thereof from a plane transverse to the piston axis and medially of the length thereof, said piston being provided

with an annular groove at approximately the plane where said taper commences, said liner being split and having a cylindrical outer surface and an inner surface tapered complementarily to the tapered portion of said piston surface, an annular groove encompassing said piston adjacent the lower edge thereof, the upper and lower edges of said liner when unworn projecting partially over said first and last mentioned grooves respectively, retaining rings in said grooves and an annular transferable shim or shims designed to be positioned in said first mentioned groove between the retaining ring therein and the upper edge of said liner, said shim or shims being transferable from said first mentioned groove to said last mentioned groove following the temporary removal of said liner for this purpose as wear takes place upon the cylindrical outer surface of said liner.

4. A piston and an adjustable liner positioned thereon, said piston being circumferentially tapered inwardly towards the base thereof from a plane normal to the piston axis and medially of the length thereof, said piston being provided with an annular groove at approximately the plane where said taper commences, said liner being split and having a cylindrical outer surface and an inner surface tapered complementarily to the tapered portion of said piston surface, an annular groove encompassing said piston adjacent the lower edge thereof, the upper and lower edges of said liner when unworn projecting partially over said first and last mentioned grooves respectively, the upper edge of said liner being stepped outwardly from the rear tapered surface thereof, a pair of retaining rings in each of said first and last mentioned grooves, an annular transferable shim or shims designed to be received in said first mentioned groove and between said retaining rings when said liner is unworn, said shims being transferable upon the temporary removal of said liner for this purpose, to said last mentioned groove and between the retaining rings therein as wear takes place upon the cylindrical outer surface of said liner, one edge of the lowermost retaining rings in said first mentioned groove being bearable against the stepped upper edge of said liner, said stepped edge providing a projecting flange acting to retain said shims in place when in said first mentioned groove and a stepped lock ring to maintain the retaining rings within said last mentioned groove in place and also the shim or shims when transferred thereinto.

DAVID BUSHBY.
